UNITED STATES PATENT OFFICE

HENRY THOMAS, OF LONDON, ENGLAND, ASSIGNOR TO U. S. SLICING MACHINE COMPANY, OF LA PORTE, INDIANA, A CORPORATION OF INDIANA

WORK HOLDER FOR SLICING MACHINES

Application filed November 8, 1926, Serial No. 146,888, and in Great Britain March 2, 1926.

This invention relates to machines for slicing meat or other commodities and especially to display trays for holding the material to be sliced, such as cooked meats, so that the unsliced piece may be removed from the slicing machine and placed in position where it may be seen by the customers and readily placed on the slicing machine when desired.

10 The object of the invention is to provide a display tray of the class named which shall be of improved construction and operation, and which shall be convenient to connect with or disconnect from the slicing machine.

15 Other objects will appear from the following description.

The invention is exemplified in the combination and arrangement of parts shown in the accompanying drawings and described in 20 the following specification and it is more particularly pointed out in the appended claims.

In the drawings:—

• Fig. 1 is a top plan view of a portion of a 25 slicing machine showing one embodiment of the present invention;

Fig. 2 is a section on line 2—2 of Fig. 1;

Fig. 3 is an elevation with parts in section showing the display tray in position on the 30 feed table of a slicing machine;

Fig. 4 is an elevation looking from the left in Fig. 3;

Fig. 5 is a fragmentary elevation showing a modified detail of construction;

35 Fig. 6 is a plan view of the details shown in Fig. 5.

The numeral 10 designates the feed table of a slicing machine having an inverted U-bracket 11 secured to the upper face therefore 40 of in which a lever 12 is mounted on a pivot pin 13. The lever 12 carries a toothed block 14 for engaging the threads of a feed screw 15. A leaf spring 16 has rolled ends 17 which project through slots 18 in the legs 45 of the U-bracket 11 and are held against displacement from the slots by screws 19. The lever 12 is provided with a projection 20 which overlies the spring 16 so that the spring operates to hold the toothed member 14 in contact with the feed screw 15. The

lever 12 is provided with a handle 21 by means of which the toothed member 14 may be raised out of engagement with the feed screw. The feed table 10 carries a removable display tray 22 having a portion 23 bent upwardly at one side forming an upstanding wall to which a socket member 24 is secured by rivets 25 at one side of the forward end of the feed table. The display tray 22 may be provided with diagonally directed ribs 22' to assist in holding material in place on said display tray. The feed table 10 has a guide member 26 against which the wall 23 of the tray 22 bears, and the wall 23 is provided with a bifurcated bracket 27 which engages a slot 35 at the base of the handle member 28 secured to the guide 26 for holding the tray 22 in place on the feed table. A screw or other lug 29 projects from the forward end of the guide 26, and the bearing member 24 is provided with a lip 30 which projects beneath the screw 29 to hold the forward end of the tray 22 in position.

The side of the tray opposite the guide 26 has spaced projecting ears 31 which are positioned respectively in front and rear of the U-bracket 11. It will be seen from Fig. 2 that the end rolls 17 of the spring 16 project beyond the ears 31 so that the spring serves to hold the display tray 22 against upward movement. To position the tray in place on the feed table, the side adjacent the guide 26 is placed in position while the side having the ears 31 is canted upwardly with the parts 27 and 30 in engagement with their corresponding holding members on the guide 26. The upwardly canted side of the tray is then moved downwardly, forcing the ears 31 past the projecting rolls 17 of the spring 16. The rolls will yield to permit the ears to pass and will form a spring catch to retain the tray in place. To remove the tray, the handle 21 may be lifted to depress the central portion of the spring 16 which will thus draw the ends of the spring inwardly and free the ears 31. The side of the tray may then be lifted to permit it to be shifted laterally to release the holding members 27 and 30.

For clamping a piece of meat or other material on the display tray 22, a standard 32 is 100

held in the socket member 24 in position to rotate about an upright axis in the socket member. A clamp 33 is mounted to slide vertically on the standard 32 and is held in vertically adjusted positions by any suitable catch member 34. The upper portion of the standard 32 is preferably angular in cross section to hold the clamp 33 from rotating on the standard. The standard, however, may 10 be rotated in the socket 24 to move the clamp away from the tray to permit a piece of meat or other material to be readily placed on the tray or removed therefrom. The socket member 24 may be provided with a spring-held 15 pin 35 arranged to engage depressions 36 in the lower end of the standard 32 to hold the standard in its adjusted positions as shown in Figs. 5 and 6.

I claim:—

20 1. The combination with the feed table of a slicing machine, of a display tray mounted on said feed table, inter-engaging means on said feed table and display tray for holding one side of said display tray in position on said feed table, a bracket at the opposite side of said feed table, spaced ears on said display tray for engaging said bracket, and a spring catch mounted on said bracket for engaging said ears to hold said opposite side of said 25 display tray in position on said feed table.

2. The combination with the feed table of a slicing machine, of a display tray mounted on said feed table, inter-engaging means on said tray and feed table at one side of said 30 tray, a bracket on said feed table at the opposite side of said tray, a lever pivoted in said bracket, a leaf spring mounted in said bracket and having rolled ends projecting at opposite sides thereof, and ears on said tray for 35 engaging said rolled ends to hold the side of said tray adjacent said bracket in position on said feed table said lever being for the purpose of operating said leaf spring.

3. A removable display tray for a slicing 40 machine carriage comprising a base member, means on one side of said base member adapted to interlock with means on said carriage, and spaced ears on the opposite side of the base member adapted to engage and be held by a catch on said carriage, said catch engaging the upper surfaces of said ears and exerting a force thereon in a downward direction.

4. A slicing machine carriage comprising a 45 base member, a removable display member carrying a clamping means adapted to be removably mounted on the base member, means for locking the display member on said base member comprising means at one side of said 50 display member interlocking with means on the corresponding side of the base member, a loosely mounted spring mounted at the other side of the base member having means urging it downwardly against the base and 55 arranged to have its opposite ends engage and

hold means on the corresponding side of the display member.

5. A slicing machine carriage comprising a base member, a removable display member carrying a clamping means adapted to be removably mounted on the base member, means for locking the display member on said base member comprising means at one side of said display member interlocking with means on the corresponding side of the base member, a loosely mounted spring mounted at the other side of the base member having means urging it downwardly against the base and arranged to have its opposite ends engage and hold means on the corresponding side of the display member, said means for urging the spring downwardly comprising a lever pivoted to the base and held against movement away from the spring by its engagement with a part on the base. 70 75 80 85

6. The combination with the carriage of a slicing machine, of a removable display tray mounted thereon, spaced ears on said display tray, and a single releasable catch engaging both of said ears. 90

7. The combination with the carriage of a slicing machine, of a removable display tray having a plurality of means on one side thereof engageable with a plurality of projections on the carriage, a plurality of spaced ears on the opposite side of the display tray, and a spring having curled ends loosely surrounding screws mounted on the base, the over-all length of the spring being greater than the distance between the ears so that as the spaced ears are forced down over the ends of the spring the latter is compressed and will expand again as the ears pass thereover, to engage and hold the spaced ears and as a result the display tray in yielding engagement with the carriage. 95 100 105

8. The combination with the carriage of a slicing machine, of a removable display tray having a plurality of means on one side thereof engageable with a plurality of projections on the carriage, a plurality of spaced ears on the opposite side of the display tray, a spring having curled ends loosely surrounding screws mounted on the base, the over-all length of the spring being greater than the distance between the ears so that as the spaced ears are forced down over the ends of the spring the latter is compressed and will expand again as the ears pass thereover, to engage and hold the spaced ears and as a result the display tray in yielding engagement with the carriage, and a means for shortening the over-all dimension of the spring to permit the tray to be removed from the carriage. 110 115 120 125

9. The combination with the carriage of a slicing machine, of a removable display tray having a plurality of means on one side thereof engageable with a plurality of projections on the carriage, a plurality of spaced ears 130

on the opposite side of the display tray, a spring having curled ends loosely surrounding screws mounted on the base, the over-all length of the spring being greater than 5 the distance between the ears so that as the spaced ears are forced down over the ends of the spring the latter is compressed and will expand again as the ears pass thereover, to engage and hold the spaced ears and as a 10 result the display tray in yielding engagement with the carriage, and a pivoted lever engaging said spring for changing the over-all dimension of the spring so that the display tray may be removed from the carriage.

10. The combination with the carriage of a slicing machine, of a removable display tray having a plurality of means on one side thereof engageable with a plurality of 20 projections on the carriage; a plurality of spaced ears on the opposite side of the display tray, a spring having curled ends loosely surrounding screws mounted on the base, the over-all length of the spring being greater than the 25 distance between the ears so that as the spaced ears are forced down over the ends of the spring the latter is compressed and will expand again as the ears pass thereover, to engage and hold the spaced ears and as a result 30 the display tray in yielding engagement with the carriage, and a pivoted lever carrying a tooth engaging a feed screw on the carriage adapted to engage the spring for changing the over-all dimension of the spring so that 35 the display tray may be removed from the carriage.

11. A display tray for slicing machines comprising a base member adapted to be attached to the carriage of a slicing machine, 40 an upright rotatably carried by the base member, and a clamp member slidably along but non-rotatably mounted on said upright adapted to clamp a substance to be sliced on said tray.

45 12. A display tray for slicing machines comprising a base member adapted to be attached to the carriage of a slicing machine, an upright rotatable to various predetermined positions, a clamp non-rotatably mounted on said upright but slidable therewith, and means for holding said clamp in adjusted position along said upright.

50 13. In a slicing machine the combination with a feed table, of a display tray mounted on said feed table, a bracket disposed at one side of said feed table, spaced ears on said display tray for engaging said bracket and for preventing longitudinal movement of said display tray relative to said feed table, and 55 a spring catch adapted to engage said spaced ears to prevent vertical movement of said display tray away from said feed table.

14. In a slicing machine the combination 60 with a feed table, of a display tray mounted on said feed table, a bracket on said feed

table along one side of said display tray, a lever pivoted on said bracket, ears on said tray arranged in close proximity to said bracket, and a spring on said bracket for engaging said ears, said lever being for the 70 purpose of operating said spring.

15. A device as set forth in claim 14 which includes a feed screw for feeding said feed table and in which said lever is provided with a nut for engaging said feed screw. 75

16. In a slicing machine the combination with a base member, a removable display member mounted on said base member, and means for locking said display member on said base member comprising a bracket on one side of said base member, a loosely mounted spring mounted on said bracket and adapted to engage said display member and hold the same downwardly on said base member, said spring being adapted to have its opposite ends in engagement with said display member. 80

17. In a slicing machine the combination with a feed table, of a display tray having a plurality of projections on one side thereof, and a spring having curled ends thereon loosely surrounding retaining means on said table, the overall length of said spring being greater than the distance between said 90 projections, said spring being compressible 95 in the direction of its longitudinal dimension so that the projections on the display tray may be brought into engagement with said spring and moved downwardly over the opposite ends thereof to bring said display tray into desired position on said table and so that after said projections have passed over the ends of said spring the spring will expand to its normal dimensions and prevent accidental removal of said display tray from said table and hold said display tray in position on said table. 100

18. A device as called for in claim 17 in which a means is provided for decreasing the overall dimension of the spring to permit removal of the tray from said table. 110

19. In a slicing machine, the combination with a feed table, of a toothed member operatively connected to said table for engaging a feed screw, a lever forming an extension of said toothed member adapted to operate said toothed member into and out of engagement with said feed screw, a display tray removably mounted on said feed table, and a latch for holding said display tray in position on said feed table, said lever being operatively connected to said latch so that said latch is moved to release the display tray from its operative position on said feed table simultaneously with the movement of the feed screw into an inoperative position. 115

20. In a slicing machine, the combination with a feed table adapted to be slidably mounted on a substance supporting table, a feed nut movably mounted on said feed table 120

and adapted to engage a feed screw for feeding the feed table along said substance supporting table, a display tray releasably mounted on said feed table, means for releasably holding said display tray on said feed table, and operative connections between said releasable means and said feed nut for

releasing said display tray from said feed table when the feed nut is moved out of engagement with said feed screw, said feed nut being adapted to release said display tray without releasing the feed table from the supporting table. 70
